(57) CLAIM

The ornamental design for a face mask as shown and described.

DESCRIPTION

FIG. 1 is a front view showing the new design for a face mask;

FIG. 2 is a back view thereof;

FIG. 3 is a left view thereof, the right view being a mirror image;

FIG. 4 is a top view thereof; and,

FIG. 5 is a bottom view thereof.

The portions of the face mask in FIGS. 1-6 shown in broken lines are included to show features that form no part of the claimed design.
